UNITED STATES PATENT OFFICE.

CLIFFORD G. CARLSON, OF JAMESTOWN, NEW YORK.

MEDICINE CABINET.

Application filed June 9, 1923. Serial No. 844,380.

This invention relates to an improvement in a medicine cabinet, and more particularly in medicine cabinets of the knock-down type provided with an adjustable door containing a mirror and having a concealed hinge.

While medicine cabinets of this general type are not new, it has been observed that the mirror in the door, being limited in position by the hinging of the door to the cabinet, is not adapted to the best use under all conditions and furthermore, it is not possible to so arrange the mirror in a fixed door that it can be used for shaving under the best lighting conditions, while at the same time keeping the cabinet open so that the shaving articles can be left upon one of the shelves.

The chief object of this invention is to provide in connection with a medicine cabinet a door in which a mirror is installed, said door being so hinged that the mirror in it can be brought into any desired position, thus permitting it to be adjusted to suit any lighting conditions, and further, the door and cabinet being so constructed that the door can be hinged at either side by simply reversing the cabinet.

A further object of this invention is to provide a knock-down medicine cabinet, the walls of which are assembled without the use of bolts or rivets into a rigid structure, when the location to which the cabinet is to be installed has been reached.

Other objects reside in the particular details of construction set forth in the following description taken in connection with the drawings which form a part thereof, and in which—

Fig. 1 is a perspective view of one embodiment of this invention, the door being shown open;

Fig. 2 is an enlarged cross section of this embodiment, the door being closed;

Fig. 3 is an enlarged vertical sectional view of the cabinet, shown in Fig. 1;

Fig. 4 is a sectional view taken along the line 4—4 of Fig. 2;

Fig. 5 is a sectional view taken along the line 5—5 of Fig. 2;

Fig. 6 is a rear view of the door and mirror detached from the cabinet;

Fig. 7 is an enlarged view of the hinge, by which the door is swung upon the cabinet.

Fig. 8 is a perspective view of the cabinet, the door and outer facing being removed;

Fig. 9 is a perspective view of the top or bottom wall of the cabinet; and

Fig. 10 is a diagrammatical view illustrating certain of the various positions which the mirror carrying door can assume.

Referring to the drawings, the reference numeral 10 is used to designate a cabinet having a door 11 hinged thereto, in which door is installed a mirror 12. The cabinet 10 comprises a facing plate 13, top and bottom walls 14 and 15, rear wall 16 and side walls 17 and 18.

As shown particularly in Figs. 2 and 3, all these walls are made of sheet metal stamped into suitable form. The edges of the rear wall 16 are bent at an acute angle to form the flanges 19, with which the top, bottom and side walls engage, as will be pointed out below. The rear edges of the top and bottom walls 14 and 15 and the side walls 17 and 18 are bent to provide flanges 20, and these flanges are bent along the outer edges to form the acute flanges 21.

In the side walls 17 and 18 are formed suitable blisters 25, which act as supports for the shelves 26. The outer edges of the bottom, top and side walls are offset, as shown particularly in Figs. 2 and 8, to provide flat surfaces 27 in which are formed a plurality of suitably spaced slots 28. The face plate 13, which may be formed of any desired contour, such as for example that shown in the drawing, is provided with a plurality of suitably spaced tongues 29, which enter the slots 28 in the flat surfaces 27 of the walls.

The door 11 is of the usual type, being provided with an opening 30, which is surrounded on three sides by the offset strips 31, shown particularly in Fig. 6. These strips are formed to receive the mirror 12, which is slid in place, thus closing the opening 30. Above and below the strips 31 are secured brackets 32, with which the door hinges engage, as will be pointed out below.

The hinge 33 is preferably made of a single piece of metal as shown in Fig. 7, the center portion 34 being straight and secured by a plate 35 fixed to the rear of one side of the face plate 13, by welding or in any other suitable manner, and fitting the center portion 34 so tight as to produce friction enough to hold door where it is placed. As shown

in Fig. 2, the plate 35 is provided with a pocket 36, which encloses the portion 34 of the hinge. In the side wall 18 are formed openings 37 through which the arms 38 and 39 of the hinge extend. Each of the arms 38 and 39 are connected with the center portion 34 by means of an arced portion 40 and a right angle portion 41. By the provision of the arced and right angle portions 10 the door can be swung around the axis defined by the pocket 36, the center portion 34 being freely movable therein.

At the outer end of the arms 38 and 39, are provided eyes 42, which coincide with holes 15 through the brackets 32 on the door. These portions are united by means of a nut and bolt construction 43, shown in Fig. 5, a lock ring being provided between the head of the bolt and the hinged arm, so as to provide 20 sufficient friction so that the door will stay in whatever position it is placed.

On the rear of the door 11 are provided suitable spring clips 45, which engage the arms 38 and 39 of the hinge when the door 25 is in the normal position, see for example Fig. 2. A knob 46 is provided at the side of the door opposite the hinge by which the door may be opened and closed in the usual manner, the hinge arms 38 and 39 being held 30 against the door by the clips 45.

Projecting from the rear face of the door adjacent the knob 46 is an angle plate 47 having an aperture 48 therein. On the side wall 17 is provided a snap fastener 49, the 35 tip 50 of which enters the aperture 48 when the door 11 is closed. For purposes of convenience the plate 47 is here shown secured in position by means of the nut 51 which holds the knob 46 in place. Obviously, however, other means could be employed if preferred. Opposite the knob 46 on the other side of the mirror 12 is provided a knob 52 in substantially the same vertical line as the 40 clips 45.

45 The cabinet is shipped "knocked-down" to its destination and is there assembled as follows: The flanges 21 of the top, bottom and side walls are hooked over the flanges 19 of the rear wall and then the top, bottom and 50 side walls are swung into the final position at right angles to the rear wall. The tongues 22 will enter the slots 23 and the portions 24 of the side walls beyond the slots bent to rest upon the outer faces of the top and 55 bottom walls. By bending the projecting tongues 22 against the outer faces of the side walls, the walls are held firmly in position without the use of nuts, bolts or rivets.

60 The face plate 13 is now placed upon the front of the cabinet, the flanges entering the recess defined by the offset edges of the top, bottom and side walls. The tongues 29 pass through the slots 28 and are bent over at right angles to hold the face plate in place. 65 The door 11 is now mounted upon the hinge

arms 38, 39 by the bolts 43 and the cabinet is completed.

When this embodiment of this invention is to be used as a cabinet, the door 11 will be opened by the knob 46 in the usual way, the 70 hinge swinging in the pocket 36. If, however, it is desired to adjust the door so that the mirror will be brought into the best light, this will be done by means of the knob 52, which tends to swing the door around the 75 axis determined by the bolts 43. Since the clips 45 only yieldingly hold the arms 38 and 39 against the door, it is obvious that by reason of the location of the knob 52, when that knob is pulled, the clips will leave the arms 38 and 39 and the door will then swing freely on its center axis into any position as is indicated diagrammatically in Fig. 10 which shows various positions of the door. It will be observed that either knob 80 can be used to open the door, the knob 46 causing it to turn on the axis of the pocket 36 and the knob 52 causing it to turn on that axis and also upon the axis of the bolts 43.

While one embodiment of this invention has been shown and described, I am not to be limited thereto since it is obvious that others may be made without departing from the spirit and scope of the invention as set forth in the following claims.

Having thus set forth my invention what I claim as new, and for which I desire protection by Letters Patent is:

1. In a medicine cabinet including a face plate and a door in which a mirror is installed, hinges mounted upon the inner face of said plate, openings in one wall of said cabinet through which said hinges pass, brackets on said door, means for pivotally securing the ends of said hinges to said brackets, clips on said door normally engaging said hinges and holding them against the inner face of said door, said hinges having arced portions which pass through said openings, whereby when said clips engage said hinges the hinges turn upon their connection with said plate and the door opens in the usual manner and when said clips are free from said hinges the door turns on its pivotal connections with said hinges, thus permitting the adjustment of the door horizontally at any desired angle.

2. In a medicine cabinet including a face plate and a door in which a mirror is installed, hinges mounted upon the inner face of said plate, openings in one wall of said cabinet through which said hinges pass, brackets on said door, means for pivotally securing the ends of said hinges to said brackets, clips on said door normally engaging said hinges and holding them against the inner face of said door, said hinges having arced portions which pass through said openings, whereby when said clips engage said hinges, the hinges turn upon their con-

nection with said plate and the door opens in the usual manner and when said clips are free from said hinges the door turns on its pivotal connections with said hinges, thus permitting the adjustment of the door horizontally at any desired angle, and knobs on said door at each side of said mirror adapted to be used to open said door, the use of one

knob causing the door to swing on the hinge and plate connections, and the use of the other knob causing the door to swing on both the hinge and plate connections and the hinge and door connections.

In testimony whereof I have affixed my signature.

CLIFFORD G. CARLSON.
